[57] CLAIM

The ornamental design for a spoon or similar article of flatware, substantially as shown and described.

DESCRIPTION

FIG. 1 is a front elevation view of a spoon or similar article of flatware showing my new design; FIG. 2 is a side elevation view thereof; FIG. 3 is an end view thereof; and

FIG. 4 is a cross-sectional view taken along section 4—4 of FIG. 1.

The handle design is intended for use with spoons, knives, forks and other articles of flatware.
